UNITED STATES PATENT OFFICE

HART O. BERG, OF NEW YORK, N. Y., ASSIGNOR, BY MESNE ASSIGNMENTS, TO SEAL-CONES, INC., OF NEW YORK, N. Y., A CORPORATION OF DELAWARE

APPARATUS FOR MAKING RECEPACLES

Application filed October 19, 1929. Serial No. 400,944.

This invention relates to apparatus for forming or assembling paper receptacles of truncated conical formation, and particularly to tubular holders to releasably enclose formed receptacle bodies, which holders are mounted on a carrier operative to successively position the receptacle bodies to means for forming, inserting and securing a closure or bottom disk in the larger end of the receptacle bodies and to a position for ejecting the completed receptacles from the holders, and it is an object of the invention to provide improved holders for this purpose and an adjustable mounting therefor on the carrier to correctly aline the larger end of the receptacle bodies in the holders relative to the closure forming and inserting means and the closure securing means to compensate for variations and wear in the parts.

The holders comprise longitudinal sections, and it has heretofore been the practice to mount the holder sections upon the carrier therefor whereby both sections are movable relative to each other into and out of mating relation, the sections being normally urged out of mating relation and means being provided to normally maintain the sections in closed position, and it is another object of the invention to provide an improved mounting arrangement for the holder sections whereby the one holder section is mounted in fixed position on the carrier and the other section is pivotally carried by and normally urged into mating relation with the fixed section, and to provide novel and positively operated means for moving the movable section away from the fixed section to release the receptacles from the holders after the closure disks have been secured therein.

It is a further object of the invention to provide novel means operative by the movement of the movable holder section from the fixed section to release the completed receptacles from the holder sections.

Other objects and advantages will herein-after appear.

The embodiment of the invention illustrated comprises a rotatable carrier in the form of a disk intermittently operated to success-

ively position one of a series of holders equidistantly spaced about and extending radially of the carrier to means for forming, inserting and securing a closure disk in the larger end of truncated conical receptacle bodies 55 carried by the holders and to a position to eject the receptacles from the holders. Each of the holders comprises a pair of semi-circular and pivotally connected sections with one of the sections supported in fixed position on the carrier and adapted to have adjustment circumferentially, radially and vertically of the carrier to correctly aline the larger end of the holders which project beyond the periphery of the carrier relative to the closure disk forming and inserting means and the closure disk securing means. The other holder section is yieldingly urged toward the fixedly mounted holder section to retain a receptacle body therein, and said section being adapted 70 to be moved away from the section fixedly supported on the carrier when the holders are moved by the carrier relative to the position for ejecting the completed receptacles from the holders. Due to stresses set up by the 75 subjecting of receptacle bodies in the holders to the action of the closure disk inserting and securing means the sides of the receptacle body will be caused to tenaciously adhere to the wall of the holder section, and to facilitate 80 the ejecting of the formed receptacles from the holders means are provided which are projected through opposite wall portions of the holder sections as the one section is moved away from the fixed section at the ejecting 85 position of the carrier to engage the receptacles and strip the same from the walls of the holder sections to permit of the ready ejecting of the receptacles from the holder by a stream from a source of pneumatic pres- 90 sure directed into the receptacles.

In the drawings accompanying and forming a part of this application Figure 1 is a side elevational view of a receptacle holder in receptacle enclosing position.

Figure 2 is a plan view showing the arrangement of receptacle holders on a rotatable carrier to be successively positioned thereby relative to receptacle body forming means to receive a receptacle body, to means 100

to form and insert a closure disk in receptacle bodies in the holders, to means to secure the closure disks in the receptacle bodies and to a position where the completed receptacles are ejected from the holders.

Figure 3 is an end elevational view of a receptacle holder in receptacle enclosing position showing the mounting thereof on the holder carrier and the means to move the movable section of the holder away from the fixed holder section.

Figure 4 is a side elevation, on a reduced scale, of a receptacle holder looking at the right of Figure 3.

Figure 5 is a fragmentary end view, partly in section, of a receptacle holder showing the movable section separated from the fixed section and the means to strip the receptacle from the holder sections, said means being in the position they assume when the movable holder section is moved away from the fixed section; and

Figure 6 is a sectional view of a receptacle holder, taken on the line 6-6 of Figure 3 looking in the direction of the arrows, to show the mounting thereof on the carrier.

Similar characters of reference designate like parts throughout the different views of the drawings.

In carrying out the invention there is provided a carrier in the form of a horizontal extending disk 7 having a series of receptacle holders, shown as eight in number in the present instance, equidistantly spaced about and extending radially of the disk with the outer end projecting beyond the periphery of the disk as shown in Figure 2, wherein certain of the holders are shown diametrically in dot and dash lines. The carrier disk is fixed to a shaft 8 rotatably supported in a sleeve portion 10 extending from a suitable supporting table (not shown) with a shoulder portion 9 of the shaft engaging the end of the sleeve. The shaft and thereby the holder carrier is intermittently rotated by suitable means, as shown for instance in Letters Patent #1,628,074 issued May 10, 1927, to Irving Stanley as the assignor to Sealed Containers Corporation, the assignee of the present application, to successively position the receptacle holders at the stations indicated at *a* to *h* respectively, the distance between each station being equal to the distance of each intermittent movement of the carrier disk.

At station *a* receptacle body forming means are arranged and when the holders are positioned at said station they receive a receptacle body *R* from a mandrel *M* of said means during a period of rest of the rotation of the carrier disk 7. Upon the next intermittent rotation of the carrier disk the holder with the receptacle body therein is moved to position *b* where no operation upon the receptacle occurs. By the next intermittent rotation of the carrier disk said holder is moved to sta-

tion *c* positioning the end of the receptacle body at the outer end of the holder projecting from the carrier disk in alinement with punch and die mechanism (not shown) to sever and peripherally flange a disk *D* from a web *W*, as shown in a conventional manner, and position the flanged disk *D* into the end of the receptacle body to constitute a closure or bottom disk of the receptacle.

By the two subsequent intermittent movements of the carrier disk the end of the receptacle body with the closure disk inserted therein will be moved to stations *d* and *e* in alinement with spinning means, shown in a conventional way at *S*, *S'* to fold inward an end portion of the receptacle body projecting beyond the flange of the disk *D* over the disk flange at the first spinning means *S*, and then interfolding the contiguous receptacle portion and the disk flange at the spinning means *S'*. From station *e* the holder is moved to station *f* where no operation is effected, and from said latter station to station *g* where the bottomed receptacle is ejected from the holder, as indicated at *R'* in dot and dash lines. From station *g* the holder is successively moved to stations *h* and *a*, and at said latter station again receives a receptacle body from the mandrel *M* of the body forming means.

To facilitate the positioning of the receptacle body into the holders the holders comprise a pair of longitudinal separable sections 11, 12 of semi-circular shape in cross section and conforming to the shape of the body of the receptacle to be formed, in the present instance of truncated conical form, to securely retain the receptacle body therein, the sections being pivotally connected one with the other at a marginal portion to have movement on an axis extending longitudinally of the holder by a pintle 13 extended through perforated ears 14 projecting laterally from a longitudinal edge portion of the section 11, and perforated ears 15 extended laterally from the opposed longitudinal edge portion of the section 12 engaged between the ears 14 with the pintle fixed to the ears 15 by a pin 16. The holders are arranged with the larger ends at the outer end and projected beyond the periphery of the carrier disk.

Due to the vibration of the intermittent rotation of the disk 7, and the wearing of the parts the holders during the periods of rest of the carrier disk will not aline with the closure disk inserting and securing means and thus prevent the proper securing of the closure disks in the receptacle bodies. To overcome this disadvantage the holders are mounted on the carrier disk to have adjustment in directions circumferentially, radially and vertically of the disk. To effect such adjustments of the holders on the carrier disk inverted *T* slots 17 are arranged in the top surface of the carrier disk to extend radially

inward from the periphery to adjacent the center thereof for the engagement of nuts 18 to impinge against the underside of the slot flanges and threaded onto headed bolts 19 5 extended through the reduced portion of the slots. The bolts serve to adjustably secure mounting members in the form of plates 20 for the holders upon the carrier disk, the bolts being extended through perforations in said 10 plates adjacent each corner. To permit of adjustment of the holder mounting plates in a direction circumferentially or laterally of the carrier the reduced portion of the slots 17 are of a width greater than the diameter of 15 the bolts 19 to permit movement of the bolts in a direction laterally of the slots, or in a direction laterally of the axis of the holders. To effect adjustment of the holders in a direction radially of the disk the nuts are 20 loosened through the turning of the bolts by the heads. To mount the holders on the mounting plates 20 and thereby on the carrier disk the holder sections 12 are arranged intermediate the side edges with a base member 21 integral with and extending longitudinally of the section and having a plate portion with the opposite longitudinal marginal portions extended laterally of the connecting portion of the base with the holder section 25 30 and having perforations therein adjacent the corners for the passage of threaded posts 22 threaded into the plate 20, with the holder section 12 adjustably mounted on the posts by nuts 23 threaded onto the posts abutting 35 the opposite sides of the plate portion of the base 21. By turning the nuts 23 onto or off from the posts the sections 11, 12 are adjusted in a vertical direction or raised or lowered relative to the carrier disk 7. The 40 sections are normally urged to closed position or into mating relation by springs 35 attached at the ends to pins 36, 37 fixed in and extending from the respective holder sections 11, 12.

45 To radially position a receptacle body into a holder as it is ejected from the mandrel M of the body forming means at station a, the holder sections are separated or spread against the action of the springs 35, as the 50 diameter of the sections in closed mating position is such that substantial longitudinal movement of the receptacle into the holder is impossible due to the frictional contact of the receptacle body with the wall of the 55 holder. To separate the holder sections the section 12 is arranged adjacent the longitudinal edge opposite to the pivotal connection of the sections with a bifurcated ear 24, a lever 25 being pivotally suspended from between the bifurcation legs of the ear to have 60 swinging movement on an axis extending parallel with the longitudinal axis of the holder, which movement is limited in one direction by the lever engaging a projection 65 or stop 26 extended from the base plate 21. When the sections are in receptacle enclosing position a roller 27 rotatably carried between the legs of a bifurcation of an arm 28 extending from the section 11 engages the top or end 70 of the lever 25 and urges the lever against the stop projection 26, said engagement between the lever 25 and roller 27 is yieldingly maintained by a spring 29, one end of which is attached to a pin 30 extending from the side of the arm 28 and the other end attached to an extension 31 of the pivot of the lever 25. The section 11 is moved away from the section 12 about the pintle 13 by the swinging movement of lever 25 away from the stop projection 26 thereby moving the roller carrying arm 28 in an upward direction due to the inclining of the top end of the lever by such movement of the lever, as shown in Figure 5. This movement of the lever is effected by a 80 roller 32 rotatably carried in a bifurcated lower end of the lever riding up a cam 33 mounted on the peripheral portion of an extended drum shaped portion 34 of the sleeve 10, as shown in Figure 3, and arranged relative to the station a, as shown in Figure 2. The disk is intermittently rotated in a counter clockwise direction and as the lever roller 32 rides up the cam 33 the lever 25 will be 85 swung in a direction away from the stop projection 26 forcing the holder section 11 in an upward direction away from holder section 12, and when the roller rides off from the cam, which is subsequent to the engaging of the receptacle body from the mandrel into the holder, the holder section 11 will be again 90 moved into mating relation with holder section 12 with the roller 27 in engagement with the lever under the tension of the springs 29 and 35. 95

100 By the engagement of the flanged disk into the end of the receptacle body in the holder, and the engagement of the spinning means S, S' with the receptacle end in the securing of the closure disk in the receptacle body, there is imparted a force upon the holder in 105 a direction longitudinally of the holder, which tends to distort and longitudinally displace the mating relation of the holder sections. To overcome this distortion of the holder sections abutments 38 and 40 are extended laterally from the fixed holder section 12, and are preferably integral therewith the abutment 38 engaging in the rear of and with an adjoining side of an abutment 39 extended laterally from the movable holder section 11, and the abutment 40 engaging in the rear of and with the arm 28 of holder section 11. The abutments 38, 39 and 40, 28 110 115 in conjunction with the pivot ears 15 on the fixed holder section 12 engaging with the pivot ears 14 of holder section 11 not only prevent longitudinal displacement of the holder sections one relative to the other but also prevent lateral distortion of the holder sections transversely of the longitudinal axis 120 125 130

of the sections due to the forces transmitted to the holder sections through the strains and stresses of the driving torque of the spinning means. The inner faces of the abutments 39, 40 are curved to conform to the curvature of the holder sections to permit of free movement of the section 11 relative to the section 12.

From the spinning means S' the holders are successively advanced to stations f and g, and as the holders are advanced to the latter station g the lever roller 32 rides up a cam 41 similar to the cam 33, extending about the periphery of the carrier disk adjacent station g, and through said engagement of the lever 25 with the arm roller 27 will move the holder section 11 away from the holder section 12 preparatory to the ejecting of the completed or bottomed receptacle from the holder. However, due to forces exerted on the receptacle body in the holder the body is firmly impinged against the wall of the holder and tenaciously adheres thereto. Means are, therefore, provided to release or strip the receptacle from the holder sections. This means comprises an arm 42 of arcuate shape and extending through an arc of substantially 180 degrees, said arm being pivotally mounted intermediate its end on the pintle 13 approximately midway of the ends of the holder and retained on the pintle between collars 47, 47' fixed on the pintle. One end of the arm extends over and in superposed relation to the holder section 11, and the other end below the section 12. The opposite ends of the arm are bent inward in a direction toward the holder sections forming ears 43, which are adapted to be extended into openings 44 in the holder sections midway between the longitudinal edges thereof. The portion of the arm extending relative to the holder section 12 passes through an opening 45 in the base plate 21. The arm is normally maintained in position with the ears 43 within the openings 44 with the ends thereof substantially flush with the inner surface of the holder sections when the holder sections are in receptacle enclosing position by an angular stem member 46 fixed at one end in the collar 47, the opposite angle end of the stem slidably engaging a perforation in a lug 48 extended from the arm 42 and arranged below the pivotal mounting of the arm, with a knife edge pivot of a collar 49 fixed on the stem engaging the upper surface of the lug 48. The arm 42 is yieldingly maintained in a position of equilibrium with the ears 43 engaging within the holder openings by a spring 50 coiled about the portion of the stem extended below the lug 48 and confined between the undersurface of said lug and a washer 51 retained on the end of the stem. During the movement of the holder section 11 away from the section 12 the ear 43 engaging in the opening 44 of section 11 will be ex-

tended through the opening and strike against the enclosed receptacle. Upon the further movement of the holder section 11 it will engage an adjustable abutment in the form of a set screw 52 adjustably mounted in the arm 42 intermediate the ear engaging the opening 44 in section 11 and the pivotal mounting of the arm, effecting a rocking of the arm 42 on pintle 13 against the tension of spring 50, projecting the other ear 43 through the opening 44 in section 12 and thereby strip or release the receptacle from the holder section 12.

In this position the receptacle within the holder sections is loosely supported between the ears 43 of arm 42 when the receptacle is ejected from the holder by pneumatic pressure directed into the inner and open end of the receptacle by a pipe 53, only a portion of which is shown, fixed on an extension of sleeve 10 to extend in the plane of the longitudinal axis of the holder at station g, the pipe being enclosed within a housing 54 mounted on the carrier disk and arranged with a series of openings 55 adapted to be aligned with the longitudinal center of each receptacle holder.

After the ejection of the receptacle from the holder, the holder is moved by the successive movement of the carrier disk to position h where the holder sections are moved to closed position by the action of the springs 29 and 35 due to the lever roller 32 riding off from the cam 41.

From position h the holder is again positioned at station a, and during the travel thereof to station a the lever roller 32 again rides up the cam 33 thereby moving the holder section 11 away from holder section 12 to permit of the ready engagement of a receptacle body R into the holder.

It will be obvious that modifications may be made in construction and arrangement of parts without departing from the scope of the invention, and that portions of the apparatus may be used without others and come within the scope of the invention.

Having thus described my invention I claim:

1. In apparatus for forming receptacles, a carrier, and a series of receptacle holders mounted on the carrier to have adjustment longitudinally of the axis of the holders and horizontally and vertically of the longitudinal axis of the holders.

2. In apparatus for forming receptacles, a rotatable carrier, a holder for a receptacle body, and means to mount the holder on the carrier and extend radially thereof and to have adjustments laterally and radially of the axis of the carrier and in the plane of the axis of the carrier.

3. In apparatus for forming receptacles, a rotatable disk arranged with a circumferential series of pairs of parallel radially

- extending slots, and receptacle holders mounted in said slots to have adjustments therein radially and circumferentially of the disk.
4. In apparatus for forming receptacles, a rotatable disk arranged with a circumferential series of pairs of parallel radially extending slots, plates mounted in said slots to have adjustments therein radially and circumferentially of the disk, receptacle holders, and means to adjustably mount the holders on the plates to participate in the adjustments thereof on the carrier and have independent adjustment toward and away from the plates.
5. In apparatus for forming receptacles, a rotatable disk, receptacle holders, each holder comprising a pair of semi-circular and pivotally connected sections, and means to mount the holders on the disk to have adjustments radially and circumferentially of the disk and in the plane of the axis of the disk.
6. In apparatus for forming receptacles, a rotatable disk arranged with a circumferential series of radially extending slots, and receptacle holders comprising pairs of semi-circular sections pivotally connected, and means engaging a holder section and in the slots to mount the holders on the disk to have adjustments radially and circumferentially of the disk.
7. In apparatus for forming receptacles, a rotatable disk arranged with circumferentially disposed pairs of radially extending inverted T-slots in the face thereof, receptacle holders comprising pivotally connected sections of semi-circular form in cross section, and means for mounting the holders on the disk to have adjustments radially and circumferentially of the disk, comprising a plate for each holder, headed bolts extended through openings in the plates and the portion of reduced width of the slots and having threaded connection with nuts in the larger portion of the slots, said bolts having a diameter less than the width of the reduced portion of the slots and the nuts being of a width less than the larger portion of the slots, and means for mounting one section of the holders on the plates.
8. In apparatus for forming receptacles, a rotatable disk, tubular receptacle holders comprising semi-circular sections pivotally connected, and means to mount one of the sections in fixed position on the disk.
9. In apparatus for forming receptacles, a rotatable disk, and receptacle holders comprising semi-circular sections pivotally connected, one section mounted on the disk and the other section yieldingly urged toward the section mounted on the disk to receptacle enclosing position.
10. In apparatus for forming receptacles, a rotatable disk, receptacle holders mounted on the disk comprising semi-circular sections pivotally connected and arranged with abutments at the longitudinal marginal portions adapted to engage each other when the sections are in receptacle enclosing position to prevent displacement of the sections longitudinally and transversely of the axis of the sections by an endwise thrust on the holder sections.
11. In apparatus for forming receptacles, a rotatable disk, receptacle holders mounted on the disk comprising semi-circular sections pivotally connected to form a tube in receptacle enclosing position, and means supported on the pivotal connection of the sections adapted to be projected through openings in the sections and engage a receptacle enclosed within the sections by the separation of the sections.
12. In apparatus for forming receptacles, a rotatable disk, receptacle holders mounted on the disk, each holder comprising a pair of semi-circular sections, one section being fixed upon the disk and the other section pivotally connected to the fixed section, means to normally urge the sections into mating relation, cams disposed at predetermined points about the periphery of the disk, and means carried by one of the holder sections and adapted to engage the cams to move the pivoted section away from the fixed section.
13. In apparatus for forming receptacles, a rotatable disk, receptacle holders comprising pairs of semi-circular sections, one section being fixed upon the disk and the other section pivotally connected with the fixed section, means to normally urge the sections into mating relation, cams disposed at predetermined points about the periphery of the disk, a lever pivotally carried by the holder section mounted on the disk having a portion to engage the cams and a portion engaging the other holder section and adapted to move said holder section from the section mounted on the disk during the engagement of the lever with the cams to facilitate the ejecting of a receptacle from the holder.
14. Apparatus for forming receptacles as claimed in claim 13, wherein the movable holder section is arranged with an arm carrying a roller adapted to engage the lever to impart movement to the said holder section away from the holder section mounted on the disk during the engagement of the lever with the cams.
15. In apparatus for forming receptacles, a rotatable disk, receptacle holders comprising pairs of semi-circular sections, one section mounted on the disk and the other section pivotally connected with the section mounted on the disk, means to yieldingly urge the movable section into mating relation with the other section, means operative at predetermined points in the rotation of the disk to move the movable section against the action

of said yielding means, and means carried by the holders operative to engage a receptacle enclosed within a holder and release the receptacle from the holder as the movable section is moved away from the other section.

16. Apparatus for forming receptacles as claimed in claim 15, wherein the receptacle releasing means comprises an arcuate shaped arm pivotally supported intermediate the ends thereof on the pivot connection of the holder sections and arranged at the ends with ears normally engaging in openings in and terminating within the inner wall surfaces of the holder sections and adapted to be projected through the wall openings into engagement with a receptacle in a holder during the separating movement of the one holder section.

17. In apparatus for forming receptacles, a rotatable disk, receptacle holders comprising pairs of semi-circular sections pivotally connected, one section being mounted on the disk and the other section movable relative to and normally urged toward the section mounted on the disk, means to move the movable section away from the section mounted on the disk at predetermined points in the rotation of the disk, and means supported on the pivot connection of the holder sections adapted to engage and release a receptacle from the holder sections during the moving of the movable section away from the section mounted on the disk.

18. Apparatus for forming receptacles as claimed in claim 17, wherein the receptacle releasing means comprises an arcuate shaped arm pivotally supported intermediate the ends thereof on the pivot connection of the holder sections and arranged at the ends with ears normally extended into openings in the holder sections, and means to yieldingly urge the arm to a position of equilibrium with the ears terminating in the openings within the inner surface of the holder sections, the ear extending into the opening in the movable section being projected through the said opening during the initial movement of said section away from the section mounted on the disk and said movement of the movable section rocking the arm against the force of said yielding means and projecting the other arm through the opening in the section mounted on the disk.

19. Apparatus for forming receptacles as claimed in claim 17, wherein the receptacle releasing means comprises an arcuate shaped arm pivotally mounted on the pivot of the connection of the holder sections and arranged with ears at the opposite ends normally extending into openings in the holder sections, means to yieldingly urge the arm to a position of equilibrium with the ears terminating in the openings within the inner surface of the holder sections, and an adjustable abutment carried by the arm adjacent

the ear extended into the opening in the movable holder section and engaged by the movable section to rock the arm and project the other ear through the opening in the section mounted on the disk during the movement of the movable section away from said section mounted on the disk.

20. In apparatus for forming receptacles, a rotatable disk, plates mounted on the disk to extend radially thereof and to have adjustments radially and circumferentially of the disk, receptacle holders, and means to mount the receptacle holders on the plates to have adjustment toward and away from the plates.

21. Apparatus for forming receptacles as claimed in claim 13, wherein the lever is pivotally carried by the holder section adjacent one end of the lever to swingingly suspend the lever from the holder section, and a stop projecting from said holder section for engagement of and limit the swinging movement of the lever in one direction.

Signed at city of New York, in the county of New York and State of New York, this 20th day of June, 1929.
